CABINET OR THE LIKE

George E. Schaefer, Muskegon, Mich., assignor to The Brunswick Corporation, Chicago, Ill., a corporation of Delaware

Filed Sept. 20, 1961, Ser. No. 66,764

Term of patent 14 years

(Cl. D33—19)

FIG. 1.

FIG. 2.

FIG. 3.

FIG. 1 is a front elevation of a cabinet, showing my new design;

FIG. 2 is a top plan view of the same; and

FIG. 3 is a side view of the same.

The back is substantially plain and the side not shown is substantially the same as the side shown.

The characteristic feature of my design resides in the combination on the cabinet disclosed of the specific top hinged lift door having a full-length ledge-like integral handle member in association with the double sloped end panels which complement the sloping front, all as shown.

I claim:

The ornamental design for a cabinet or the like, as shown, and described.
